[57] **CLAIM**

The ornamental design for check printer and accounting machine, as shown.

DESCRIPTION

FIG. 1 is a perspective view of the top, front and one side of the check printer and accounting machine showing our new design;

FIG. 2 is a top plan view thereof;

FIG. 3 is a front elevational view thereof;

FIG. 4 is a rear elevational view thereof;

FIG. 5 is a side elevational view of said one side;

FIG. 6 is a side elevational view of the opposite side;

FIG. 7 is a bottom plan view thereof;

FIG. 8 is a perspective view similar to FIG. 1 with the top cover open; and,

FIG. 9 is a perspective view similar to FIG. 1 with the bottom cover partially open.

*FIG. 1**FIG. 2**FIG. 3**FIG. 4**FIG. 5**FIG. 6**FIG. 7*FIG. 8

FIG. 9
